UNITED STATES PATENT OFFICE.

ALBERT KLELL, OF WEST PARK, OHIO.

DESIGN FOR A HAT-PIN.

42,943.

Specification for Design.

Patented Aug. 27, 1912.

Application filed March 19, 1912. Serial No. 684,821. Term of patent 7 years.

To all whom it may concern:

Be it known that I, ALBERT KLELL, a citizen of the United States of America, residing at West Park, in the county of Cuyahoga and State of Ohio, have invented a certain new, original, and ornamental Design for a Hat-Pin, of which the following is the specification, reference being had to the accompanying drawing, forming a part thereof.

The figure is a perspective view of the hatpin, illustrating my new design.

I claim:

The ornamental design for a hatpin, as shown.

ALBERT KLELL.

Witnesses:

HENRY BARNES,
Jos. JUHASE.
